United States Patent

Des. 235,085
Patented May 13, 1975

235,085

CHAIR

Thomas Winrow, Naperville, Ill., assignor to Mohasco Corporation, Amsterdam, N.Y.

Filed Aug. 8, 1973, Ser. No. 386,810

Term of patent 14 years

Int. Cl. D6—01

U.S. Cl. D6—68

The figure is a perspective view of a chair illustrating my new design.

The back of the chair is conventionally plain while the side not shown is substantially identical to the side shown.

I claim:

The ornamental design for a chair, as shown and described.
